(57) **CLAIM**

The ornamental design for a fridge shelf display device, as shown and described.

DESCRIPTION

FIG. 1 is a top plan view of the invention;

FIG. 2 is a front elevation of the invention shown in FIG. 1;

FIG. 3 is a right side plan view of the invention shown in FIG.

1;

FIG. 4 is a front perspective of the invention shown in FIG. 1;

and,

FIG. 5 is a rear perspective of the invention shown in FIG. 1.

1 Claim, 2 Drawing Sheets

FIG. 1

FIG. 2

FIG. 3
